UNITED STATES PATENT OFFICE.

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND.

AUTOMATIC CLOSING DEVICE FOR WINDOWS.

Application filed February 9, 1924. Serial No. 691,651.

To all whom it may concern:

Be it known that I, HARRY E. CAMPBELL, a citizen of the United States, and a resident of Baltimore, county of Baltimore 5 City, and State of Maryland, have invented certain new and useful Improvements in Automatic Closing Devices for Windows, of which the following is a specification.

My invention relates to fire windows, and 10 in particular to the type of window in which the sashes will be automatically closed in the event of fire, by the action of heat on a fusible link. For the purposes of illustration, I have shown my invention as applied 15 to a window of the type described in my Patent No. 1,241,090, issued September 25, 1917.

In the accompanying drawings which 20 show an illustrative example of my invention, Fig. 1 is a sectional view adjacent one of the jambs, the top portion of the view being taken in such a way as to show the face of the jamb and the bottom portion of the view showing a section through the 25 jamb; Fig. 2 is a horizontal section of one jamb with the sashes in place; Fig. 3 is a section on line 3—3 of Fig. 2; Fig. 4 is a detailed section showing the tripping device and the manner of connecting the same with 30 the weight for the lower sash, and Fig. 5 is a section of the same parts shown in Fig. 4 but taken at right angles thereto.

In the window shown in the drawings, 2 35 is the weight box forming part of the jamb, 3 is the front cover plate forming a portion of the inner face of the jamb; 4 is the baffle portion of the inner jamb face and 5 is a member which forms a portion of the inner jamb face and is then bent around to form 40 a partition within the jamb; 6 is the weight for the lower sash 7, and 8 is the weight for the upper sash 9. The usual chain 10 is connected to the sash 9 and a corresponding chain 11 is connected with sash 7. These 45 chains run over the usual pulleys which are not shown in the drawings, as their construction and location is well known. Attached to the plate 3 is a weight separator 12, which as shown in Fig. 3 does not come all the way 50 to the top of the jamb. Near the top of the plate 3 is an opening 13 adjacent to which is located a fusible link 14 of the usual construction. One member of the link 14 is connected to a bracket 15 which in turn is

attached to the lintel 16. The lower half of 55 the link 14 is attached to closing weight 17 which under normal conditions hangs at the top of the jamb between the weight 8 and the separator 12. At its rear, weight 17 has arms 18 and 19 which may be made integral 60 with each other, but separable from the rest of weight 17, and which overlie weights 8 and 6 respectively. Chain 10 is attached directly to weight 8 in the usual manner, but interposed between chain 11 and weight 6 is 65 the trip 20.

The trip 20 has near the bottom a hook 21, the upper surface of which is made diagonal. The hook 21 is adapted to receive a loop 22 which is connected to weight 6 by 70 means of a bent wire 23. The manner in which this connection is made is clearly shown in Figs. 4 and 5. The pitch of the upper surface of hook 21 is such that loop 22 will slide off of this hook unless it is held 75 on. Normally, loop 22 is held on hook 21 by a plunger 24 which is held down into a recess formed in arm 21 by the action of a spring 25. Extending from the sides of plunger 24 is a pin 26 which engages the 80 slotted end of a trigger arm 27. Trigger arm 27 is preferably provided on its upper surface with a lug 28 so that contact with this arm will be at the outer end and will give the maximum effect. 85

In the event of a fire the solder which forms part of the link 14 will fuse and permit the two halves to separate; thereupon the weight 17 will drop; arm 18 will strike weight 8 and the combination of weights 8 90 and 17 will be sufficient to raise the upper sash 9. As the weight 17 drops, arm 19 will strike lug 28 of arm 27, thereby raising plunger 24 which will permit loop 22 to slip from arm 21, thus releasing weight 6 from 95 the lower sash 7, which will drop of its own weight.

It may be noted that by this arrangement a supplemental weight is used, but such supplemental weight is under all normal conditions held immovable by the fusible link in a position where it is out of the way and will permit full movement of the window. It is also to be noted that by this arrangement the fusible link is not subject to any 100 jerks, but is subject only to the static strain exerted on it by the stationary weight 17.

It is to be understood that the foregoing

is given by way of example only and that many modifications may be made without departing from the spirit of my invention.

What I claim is:

5. 1. In a double hung window construction, the combination of an upper sash having a weight connected to it, a lower sash having a weight connected to it through a releasing device, an auxiliary weight, a fusible link normally holding such weight in raised position, and means forming part of such auxiliary weight adapted, when said link fuses under the influence of heat, to cause such auxiliary weight to aid in raising the upper sash and adapted to operate said releasing device to disconnect the lower sash from its weight.
10. 2. In combination, a window sash, a flexible suspension member attached thereto, a weight for counterbalancing said sash, a releasable catch connecting said weight and said flexible member, an auxiliary weight suspended by a fusible member and means forming part of said auxiliary weight for releasing said catch when said auxiliary weight drops.

3. In combination, a window sash, a flexible suspension member attached thereto, a counterbalance weight for said sash, a catch connecting said weight and said flexible member, a trigger arm extending from said catch adapted when moved in relation to said catch to release said weight, an auxiliary weight suspended by a fusible link and a member forming part of said weight, adapted when said weight drops to contact with said trigger arm to release said counterbalance weight.

4. In combination, a jamb, sashes having members extending back of the inner wall of the jamb, counterbalancing means for said sashes located back of the inner wall of the jamb, an auxiliary weight within the jamb, a fusible link suspending such auxiliary weight, an opening adjacent such link whereby such link may be exposed to heat outside of said jamb, and means forming part of such weight adapted, when such link fuses, to cause one sash to rise and the other sash to drop.

HARRY E. CAMPBELL.
